(57) **CLAIM**

The ornamental design for a toy plane, as shown and described.

DESCRIPTION

FIG. 1 is a first perspective view of a toy plane showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the toy plane thereof.

The broken lines shown in the drawings depict portions of the toy plane that form no part of the claimed design.
